CLAIM

The ornamental design for a utensil handle, as shown and described.

DESCRIPTION

FIG. 1 is a perspective view of a utensil handle;
FIG. 2 is a perspective view showing only the handle thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment thereof;

FIG. 10 is a perspective view of a second embodiment showing only the handle thereof;

FIG. 11 is a front elevational view of a second embodiment thereof;

FIG. 12 is a rear elevational view of a second embodiment thereof;

FIG. 13 is a left side elevational view of a second embodiment thereof;

FIG. 14 is a right side elevational view of a second embodiment thereof;

FIG. 15 is a top plan view of a second embodiment thereof; and,

FIG. 16 is a bottom plan view of a second embodiment thereof.

The broken lines shown in the drawing views are included for the purpose of showing environmental structure that forms no part of the claimed design.

1 Claim, 14 Drawing Sheets
